SOFT FACED HAMMER

Strother C. MacMinn, Los Angeles, Calif., assignor to
New Plastic Corporation, Los Angeles, Calif., a corpo-
ration of Delaware

Application August 16, 1956, Serial No. 42,634

Term of patent 14 years

(Cl. D93—4)

FIG. 1.

FIG. 2.

FIG. 3.

Fig. 1 is a side elevational view of a soft faced hammer showing my new design;

Fig. 2 is an end elevation of the soft faced hammer, the opposite end having the same appearance, and,

Fig. 3 is a top plan view of the soft faced hammer, looking in the direction of the head.

I claim:

The ornamental design for a soft faced hammer, sub-
stantially as shown.
